STRAND TREATING MACHINE

Hans G. Sass, Krefeld, Germany, assignor to
Joh. Kleinefegers Söhne, Krefeld, Germany

Application February 1, 1955, Serial No. 485,527

7 Claims. (Cl. 203—200)

The present invention relates to strand treating machines and, more particularly, concerns a drive shaft comprising a plurality of elastic members for strand treating machines of the textile industry, especially strand washing machines.

Such devices are necessary in order to make it possible in spite of the shrinkage or stretching of the strand due to the treatment thereof, to pass such strand through the machine at a low tension, particularly without undue high tension of the strand, so as to obtain a good washing effect. Moreover, it is necessary throughout the path of the strand through the machine to maintain a certain necessary tension in order to obtain a proper running of the strand through the machine.

Washing machines of the above type are known, in which the individual members are provided with inclined running surfaces for the strand in an effort to cause the strand to be driven on the respective circumference of said member, which is necessary for meeting the above outlined conditions.

Also strand washing machines are known in which the drive shafts are composed of individual members having elastic parts such as rubber rods.

It is an object of the present invention to provide an improved driving shaft for strand treating machines which comprises a plurality of individual members, which will particularly easily and effectively adapt themselves to the prevailing conditions in the strand so as to maintain as low a tension of the strand as possible while securing a proper running of the latter through the machine.

It is another object of this invention to provide an elastic drive shaft for strand treating machines, which comprises a plurality of elastic members each of which is rather simple and relatively inexpensive and highly reliable in operation.

These and other objects and advantages of the invention will appear more clearly from the following specification in connection with the accompanying drawing in which:

Fig. 1 represents a diagrammatic section through a strand washing machine provided with an elastic drive shaft according to the invention.

Fig. 2 shows a diagrammatic transverse section through the arrangement of Fig. 1.

Fig. 3 is a section through an individual member of a drive shaft according to the invention, the elastic means of said individual member occupying a first position.

Fig. 4 is a section similar to that of Fig. 3 through an individual member, with the elastic means thereof occupying a second position.

Fig. 5 is a top view of Fig. 3 seen in the direction of the arrow A.

The primary feature of an elastic drive shaft according to the present invention consists primarily in that the drive shaft comprises individual members which by means of spring elements or resilient bars pertaining to adjacent individual members are arranged and cooperate with each other in such a manner that they form with each other

2

sheaves or cord pulleys adapted to vary the inner diameter of the groove thereof in conformity with the pulling force acting upon the strand being treated.

Referring now to the drawing in detail, the strand 2 enters the machine through two squeezer rollers 5, 6 and passes over a tension roller 7 to the elastic drive shaft generally designated 1 which comprises a plurality of elastic individual shaft members 1a, 1b . . . 1n. After the strand has passed from the tension roller 7 over the individual member 1a, the strand passes into the washing medium 4 and over a non-elastic counter shaft 3 to the second individual member 1b etc. alternately over the individual members and the counter shaft 3 up to the last individual member 1n. After having passed over said last individual member, the strand leaves this assembly and passes to a second elastic drive shaft 8 which is similar to the drive shaft generally designated 1 comprises n individual members. The strand then passes over a counter shaft 9 and alternately back to the elastic shaft 8 and counter shaft 9 until it finally passes over tension roller 10 to the delivery squeezing rollers 11 and 12.

In this particular arrangement which has been shown by way of example only, the intake and delivery squeezing rollers 5, 6 and 11, 12 respectively and also the elastic shafts 1 and 8 are driven. One or two tension rollers 7 and 10 may be employed for controlling the driven rollers as is known per se in connection with control arrangements for tensioning rollers.

As will be particularly evident from Figs. 3 and 4, the individual members of the shaft 1 are substantially composed of supporting discs 14 fixedly connected in spaced relationship to each other to the drive shaft 13. Connected to the peripheral portion of the discs or wheels 14 in any convenient manner, for instance by riveting, welding, or screwing, are elastic laminated spring members or bars 15 of appropriate material as for instance stainless spring steel. These spring members which may have any desired profile are substantially evenly distributed over the circumference of the discs or wheels 14 as is shown for instance in Fig. 5. As will also be evident from Figs. 3 and 4, the spring members 15 and the discs 14 are so arranged that they form a groove-like path for the strand to be treated. The bending characteristic of the spring members or bars 15 may according to the invention be determined by correspondingly shaped members 16 carried by the periphery of the discs or wheels 14. It will be evident that the shape and material of said members 16 will determine the control of the spring members 15.

According to a further development of the invention, each pair of discs or wheels 14 has interposed therebetween a disc-like member 17 which limits the extent to which the spring members or bars 15 may bend through as is clearly indicated in Fig. 4. These abutment members 17 may be provided with a hub serving as spacer between the wheels or discs 14. It will be clear that by means of the disc-like abutment member 17 damage to the elastic bars 15 will be avoided which otherwise might occur particularly when starting or setting the machine.

If desired, the elastic individual members 1a . . . 1n of the drive shaft may also be designed with a few, for instance 6, spring members or bars only, in which instance an elastic shaft member is obtained with a reel-like effect which member will impart upon the strand an oscillating movement favorable to the washing action.

The function of an elastic drive shaft according to the invention will best be understood from Figs. 3 to 5.

The manner in which the strand is passed through the washing machine and runs over the elastic drive shaft 1 has been generally outlined above. The circumferential speed of the drive shaft 1 with regard to the elastic spring

members 15 when the latter are in their non-bent or rest position, is somewhat higher than the circumferential speed of the feeding squeezer rollers 5, 6. Consequently, when the strand passes through the machine, a certain bending through of the spring members 15 must automatically occur as a result of the temporarily occurring increased tension of the strand due to the initial differences in speed. If the strand during the treatment does not change its length, the bending of the spring members 15 at the circumference of the individual members 1a . . . 1n will be the same, the resulting force of all bent through spring members at the circumference of an individual member will be twice the pulling force in the strand. The differences in speed between the delivery squeezer rollers 5, 6 and the elastic drive shaft 1 in unloaded condition is decisive for the tension in the strand at the first member of the elastic drive shaft.

When the strand shrinks during the treatment, the individual members 1b . . . 1n of the drive shaft 1 will bend further according to the change in the length of the strand whereby the diameter of the sheaves or pulley rolls formed by the individual members 1a . . . 1n will be reduced. As a result thereof, the circumferential velocity of said sheaves or pulley rolls will be adapted to the speed of the strand which has been changed due to the shrinkage. Aside from the continually but only slightly increasing tension of the strand due to the continually increased bending through of the spring elements of the individual members 1b . . . 1n, the strand will be nowhere unduly stressed.

If, on the other hand, the strand stretches during the process, the reverse procedure will occur and thus a slight decrease in the tension of the strand will occur. However, by correspondingly dimensioning or controlling the tension of the strand at the first elastic individual member 1a, the necessary tension for a proper running of the strand can be maintained at any point.

The design of the elastic shaft in conformity with the present invention, especially the elastic spring elements or bars of the individual members 1a . . . 1n, the variation of the characteristic of the bendability of the spring elements by the members 16, and the increased safety by the abutment members 17 limiting the maximum bending of the spring elements, a highly improved elastic shaft for strand treating machines is obtained which greatly improves the operation of such machines.

What I claim is:

1. In combination with a drive shaft for strand treating machines: a plurality of rotatable members supported by and connected to said shaft in spaced relationship to each other, and a plurality of sets of resilient bar-like members having one end thereof connected to and supported by said rotatable members so that the bar-like members of each two adjacent sets of each two adjacent rotatable members are inclined in opposite direction and are located in intersecting planes with the points of intersection located substantially on a circle having a diameter less than the diameter of said rotatable members thereby causing the resilient members between each two adjacent rotatable members to define with each other a yieldable groove-like path for the strand to be treated.

2. In combination with a drive shaft for strand treating machines: a plurality of rotatable members supported by and connected to said shaft in spaced relationship to each other, a plurality of sets of resilient bar-like members respectively connected to said rotatable members, the resilient members of each two adjacent sets being inclined in opposite direction and respectively having their free ends extending into the space between each two re-

spective adjacent rotatable members so as to cross each other to thereby define with each other a yieldable groove-like path for the strand to be treated, and a plurality of reinforcing members interposed between said rotatable members and the respective resilient members pertaining thereto for controlling the bending of said resilient members, said reinforcing members being shorter than said resilient members.

3. In combination with a drive shaft for strand treating machines: a plurality of rotatable members supported by and connected to said shaft in spaced relationship to each other, a plurality of sets of resilient bar-like members respectively connected to said rotatable members, the resilient members of each two adjacent sets being inclined in opposite direction and having their respective free ends extending into the space between each two respective adjacent rotatable members so that the free ends of the resilient members of each two adjacent rotatable members cross each other at a certain angle to thereby define with each other a yieldable groove-like path for the strand to be treated, and disc-like abutment members interposed between each two adjacent rotatable members and arranged for abutment with the adjacent resilient members crossing each other to thereby limit the extent to which said respective resilient members crossing each other may bend through.

4. A drive shaft according to claim 3, in which said disc-like abutment members are provided with hubs serving as spacers between two adjacent rotatable members.

5. In combination with a drive shaft for strand treating machines: a plurality of wheel-like members arranged in spaced relationship to each other and connected to said shaft, the circumferential portions of said wheel-like members having a contour tapering in radial direction thereof, a plurality of resilient bar-like members substantially evenly distributed over the circumference of said wheel-like members and extending from said tapered circumferential portions along the taper thereof to opposite sides of said wheel-like members, said resilient bar-like members respectively having one end thereof connected to the peripheral tapered portions of said wheel-like members and having their other end extending between said wheel-like members and crossing with the bar-like members of the respective adjacent wheel-like member, the arrangement being such that the resilient bar-like members crossing each other define with each other a groove-like circular path for the strand to be treated.

6. In combination with a drive shaft for strand treating machines: a plurality of wheel-like spaced supporting members supported by and connected to said shaft for rotation therewith, and a plurality of sets of resilient bar-like members, said sets being respectively carried by said wheel-like supporting members, said resilient bar-like members having one end thereof connected to said wheel-like supporting members along an incline so that the free ends of each two adjacent sets of said resilient bar-like members cross each other, the resilient bar-like members on each of said rotatable wheel-like supporting members being relatively widely spaced from each other along the circumference of said wheel-like supporting members and extending into the space between the respective adjacent supporting members.

7. A drive shaft according to claim 6, in which at least some of said wheel-like supporting members carry two sets of resilient bar-like members extending from the peripheral portions of said wheel-like supporting members to both sides thereof.
